UNITED STATES PATENT OFFICE.

EDWARD HOLM, MAGNUS JORANSSON, AND EMIL ANDERSSON, OF CHICAGO, ILLINOIS, ASSIGNORS, BY MESNE ASSIGNMENTS, TO SAID HOLM.

EMBOSSING DEVICE FOR LAUNDRY-WORK.

SPECIFICATION forming part of Letters Patent No. 410,551, dated September 3, 1889.

Application filed February 21, 1889. Serial No. 300,725. (No model.)

To all whom it may concern:

Be it known that we, EDWARD HOLM, a citizen of the United States, residing at Chicago, in the county of Cook and State of Illinois, and MAGNUS JORANSSON and EMIL ANDERSSON, both subjects of the King of Sweden, now residing at Chicago, in the county of Cook and State of Illinois, have made certain new and useful Improvements in an Embossing 10 Device for Laundry-Work, of which the following is a full, clear, and exact description, that will enable others to make and use the same, reference being had to the accompanying drawings, forming a part of this specification.

The object of this invention is to provide a domestic device for embossing or ornamenting laundry-work by producing on the finished surface of the article a design in imitation of embroidery or fancy work.

Figure 1 is a side elevation of a device embodying our improved features, and Fig. 2 an end elevation.

Referring to the drawings, A represents a 25 bracket-frame, consisting of the top part a, the sides a' a², extending downwardly therefrom, and the lugs a³ a⁴, projecting upwardly from each end.

The embossing-rollers B B' are loosely 30 mounted on shafts b b', which are in turn journaled in the respective sides of the bracket-frame, the rollers being inserted between said sides. These rollers are provided on their peripheries adjacent to the ends with 35 the designs or configurations d d'. These designs may be similar in character or of different configurations, as illustrated in Fig. 1. The entire surface of the roller may be covered by the designs or spaced, as may be desired.

It is obvious that any number of rollers 40 may be used, each having a different design, in connection with the same bracket-frame, as one set can be conveniently removed and replaced by another. One roller may be used;

but the arrangement of a set or pair, as shown, is preferred, as the device will support itself in an upright position, especially when placed on the stove to be heated.

The respective ends of the curved handle 50 C are inserted and secured in the lugs a³ a⁴, formed on the upper side of the bracket-frame.

This arrangement provides a hand device which is as convenient an article as the ordinary sad or polishing iron, and may be used 55 for the ordinary domestic purposes or in public laundries.

This device will be especially useful in imprinting ornamental designs on collars, cuffs, 60 shirt-bosoms, and other articles of wearing-apparel, and also for imitating the usual expensive embroidery on pillow-shams and similar articles. The designs thus imprinted will last for an indefinite time, will not injure the 65 fabric, and will of course entirely disappear in the process of laundering.

The rollers are first heated to the proper temperature and then pressed upon and rolled over the surface to be ornamented immediately after the process of polishing.

Having thus described our invention, what we claim as new, and desire to secure by Letters Patent, is—

In a device for the ornamentation of laundry-work, the combination, with the bracket-frame, consisting of the top part a, the sides a' a², extending downwardly therefrom, and the lugs a³ a⁴, rising upwardly from each end, of the embossing-rollers provided with designs 75 or configurations, as described, the shafts upon which said rollers are loosely mounted, and the curved handle C, substantially as and 80 for the purpose set forth.

EDWARD HOLM.
MAGNUS JORANSSON.
EMIL ANDERSSON.
